ROLLER SKATE

Frank A. Bentzlin, St. Paul, Minn.

Application May 25, 1935, Serial No. 23,397

1 Claim. (Cl. 208—173)

This invention relates to roller skates of the kind having a single row of aligned rollers and an object is to provide a skate of this type involving certain means for adjusting the rollers in arcuate arrangement longitudinally to provide floor contact corresponding to ice-surface contact of ice-skates, particularly skates of the kind used for figure or fancy skating.

Other features include front and rear brake or stop means, certain roller mounting having easy adjustment for necessary rolling qualities, a novel roller tire and mounting therefor and a simple and efficient skate frame construction, all as hereinafter fully set forth reference being had to the accompanying drawing, in which:—

Fig. 1 is a side elevation of my improved skate. Fig. 2 is a bottom view of Fig. 1. Fig. 3 is a transverse sectional detail view of the skate frame near the heel plate, about as on line 3—3 in Fig. 2. Fig. 4 is a transverse sectional view through the sole plate, about as on line 4—4 in Fig. 2. Fig. 5 is an elevation of one of the rollers and its shaft, the upper half being in section. Fig. 6 is a side elevation of one of the rollers. Fig. 7 is a fragmentary, enlarged side view of a portion of the skate frame at one of its recesses in which a roller is retained.

Referring to the drawing by reference numerals, like parts being designated in the various views by identical numbers, the skate frame is preferably one-piece including a sole plate 8, a heel plate 9, from which extend downwardly and integrally a downwardly open channel 10, which between the sole and heel plate is of inverted U-shape in cross section (see Fig. 3). The sole plate and said channel may further be solidly braced by brackets 10B.

In the type of skate illustrated, the sole and heel parts are provided with a number of apertures 11 for riveting or otherwise attaching the skates permanently to a shoe 12, but it will be readily understood that the skate may have other means for securing it to a shoe all well known in the art.

At the front and rear termini of the channel 10 its walls are extended forwardly and rearwardly to retain, removably, between the respective end parts a toe-block 13 and a heel-block 14 exposed forwardly and rearwardly and downwardly at a predetermined level, each block being made preferably of a piece of hard rubber and tapered to both ends. The blocks may be retained by screws 15 and are reversible so that either end may be exposed downwardly.

The parallel, lower edges of the channel 10

are preferably arcuate the channel being widest (vertically) at its center and said edges curving upwardly toward front and rear ends. In said lower edge parts is provided a series of transversely registering pairs of vertical slots 16, between each pair of which is adjustably and removably retained a roller shaft 17 of which the reduced and threaded outer ends are within the slots and project therefrom for receiving a nut 18 exteriorly of the channel.

Adjacent the said slots 16 the exterior channel walls are serrated or corrugated as 10C (Fig. 7) for the purpose of preventing slippage of the roller shaft 17 this being made more positive by using under each nut 18 a washer 19 of the type having corrugated or roughened faces. Thus a roller may be positively and securely retained in any desired position in and between a pair of slots 16. The purpose of this is to enable a skater to set the rollers in any suitable arcuate alignment or even in a straight line if so desired.

Each roller comprises in part a rubber tire or rim 20 the tread of which is formed arcuate in transverse section and said tread having a series 25 of circular grooves as best shown in Figs. 2, 5, and 6.

The inner part of each ring is reduced in thickness to be clamped between a flange 21F of the roller hub or outer ball-race 21 and a ring 22 threaded on said ball race opposite its fixed flange 21F. 21G is a single groove in the bore of 21 (centrally) comprising the outer race for a series of balls 25, the inner race being a corresponding groove formed between adjacent ends of two 35 bushings 23R and 23L threaded on the central part of the shaft 17 (see Fig. 5) and retained by a pair of nuts 24 also threaded on said shaft. It is obvious that adjustment of the bushings 23R and 23L provides for proper adjustment and 40 contact with the balls 25 to keep the latter at all times in proper, smooth rolling contact. A single central ring of balls is preferred, the row of rollers being in alignment under the skater's foot and their ball bearings thus carrying the 45 skater's weight in most efficient manner longitudinally of and centrally under the foot.

The feature of adjustability to set the rollers in predetermined alignment, in a curvature, as represented by the dotted line 26 in Fig. 1, is 50 stressed. This curvature, as stated, approximates the curvature of an ice skate blade but in this construction said curvature is variable as desired. It is well known that ice-skating and roller-skating hitherto have been very different requiring 55

different motion and sway to attain speed and accomplish fancy figure skating. An object of this invention is to provide roller skates the use of which is comparable or similar to ice-skating.

5 The tires or rings 20 of this skate are preferably made of comparatively tough or hard rubber but with sufficient yielding qualities so that the skater's weight causes friction contact to approximately equal the corresponding contact 10 of ice skates.

Assuming that the skate is tipped sidewise during skating, it is obvious that the outer bead and adjacent bead will bear the weight efficiently and eliminate falling because of side-slip or angular 15 pressure.

Normally, in the use of this skate, two rollers contact the floor, or three if the longitudinal curvature 26 is slight. Obviously if a skater is executing fancy figures or jumps, even four rollers 20 may contact the floor for instance at impact when descending from a leap. Thus resistance to any unusual stress is automatically increased when needed and danger of side slip is eliminated.

It is also possible to pivot on any one roller 25 the adjacent rollers providing light friction contact during pivoting to steady such action and control it.

It will now be readily seen that in regular skating with this type of skate, taking strokes is done 30 similarly to ice-skating, only one pair of rollers on each skate bearing the weight of the skater at any time.

Referring again to the toe and heel brake and pivot blocks 13—14 it is preferred to clamp them

between the end parts of the channel frame by means of the screws 15 passing through elongated slots 28 allowing for setting the blocks in desired spaced relation to the floor 29. The downwardly exposed end of either block contacts the floor for braking or pivoting purposes when the skater tips his foot forward and down or otherwise, as needed, to contact said blocks.

Modifications within the scope of the following claim may be made without departing from 10 the scope and spirit of the invention.

I claim:

A roller skate comprising an elongated channel shaped main frame of inverted U-shape in cross section, means in the web of said main frame 15 for securing it to the heel and sole parts of a shoe, the horizontal registering lower edges of said main frame being arcuate to correspond to the curvature of an ice skate blade and being provided with horizontally registering pairs of 20 upwardly directed notches, each said pair of notches being adapted to retain the shaft of a suitable roller, all of said rollers being in tandem and in selective arcuate arrangement, and means on the shaft of each roller adjacent said notches 25 for adjusting and retaining said rollers in variable arcuate arrangement, said last named means comprising in part a series of corrugations in said main frame adjacent each of said notches and providing a friction hold for roller shaft retaining means, to hold each roller at a predetermined height relative to the other rollers and to vary the arcuate alinement of said rollers.

FRANK A. BENTZLIN.
